[57] CLAIM

The ornamental design for a surveying instrument, as shown and described.

DESCRIPTION

FIG. 1 is a typical side elevational view of a surveying instrument showing my new design in the closed position;

FIG. 2 is a top plan view thereof;

FIG. 3 is a bottom plan view thereof;

FIG. 4 is a front elevational view thereof with the inner member extended in an operational position;

FIG. 5 is a rear elevational view of FIG. 4;

FIG. 6 is a right side elevational view of FIG. 4;

FIG. 7 is a left side elevational view of FIG. 4;

FIG. 8 is a front elevational view of another embodiment of my new design of FIGS. 1-7 in the closed position;

FIG. 9 is a rear elevational view thereof;

FIG. 10 is a top plan view thereof;

FIG. 11 is a bottom plan view thereof;

FIG. 12 is a front elevational view thereof with the inner member extended in an operational position;

FIG. 13 is a rear elevational view of FIG. 12;

FIG. 14 is a right side elevational view of FIG. 12;

FIG. 15 is a left side elevational view of FIG. 12.
